UNITED STATES PATENT OFFICE.

WILLIAM W. CROWL, OF WELLSBURG, WEST VIRGINIA.

DESIGN FOR A LAMP-CHIMNEY.

● 57,114.

Specification for Design.

Patented Feb. 22, 1921.

Application filed November 8, 1918. Serial No. 261,721. Term of patent 3½ years.

To all whom it may concern:

Be it known that I, WILLIAM W. CROWL, a citizen of the United States of America, residing at Wellsburg, in the county of Brooke and State of West Virginia, have invented a new, original, and ornamental Design for Lamp-Chimneys, of which the following is a specification, reference being had to the accompanying drawings, forming part thereof.

The figure is an elevational view of a lamp chimney showing the new design.

I claim—

The ornamental design for a lamp chimney substantially as shown.

In testimony whereof I affix my signature.

WILLIAM W. CROWL.
